(57) **CLAIM**

The ornamental design for a portable electric driver, as shown and described.

DESCRIPTION

FIG. 1 is a perspective view of the portable electric driver according to the invention;

FIG. 2 is a left side view thereof;

FIG. 3 is a right side view thereof;

FIG. 4 is a front side view thereof;

FIG. 5 is a rear side view thereof;

FIG. 6 is a top view thereof; and,

FIG. 7 is a bottom view thereof.
